UNITED STATES PATENT OFFICE.

CLINTON G. WILDERSON, OF LEETONIA, OHIO, ASSIGNOR TO THE CRESCENT MACHINE COMPANY, OF LEETONIA, OHIO, A CORPORATION OF OHIO.

CUTTER-HEAD.

1,147,473.

Specification of Letters Patent. Patented July 20, 1915.

Application filed June 18, 1911. Serial No. 634,173.

To all whom it may concern:

Be it known that I, CLINTON G. WILDERSON, a resident of Leetonia, in the county of Columbiana and State of Ohio, have invented 5 a new and useful Improvement in Cutter-Heads, of which the following is a full, clear, and exact description, reference being had to the accompanying drawings, forming part of this specification, in which—
10 Figure 1 is an end view partially in section of one form of my improved cutter head. Fig. 2 is a side elevation of the same. Fig. 3 is a perspective view of one of the keepers. Fig. 4 is a similar view of one of 15 the auxiliary keepers. Fig. 5 is a perspective view of the hand wrench for adjusting the knives and clamping screws; and Fig. 6 is a side elevation, partially in section, of a modified form of cutter head.
20 This invention relates to an improvement in cutter heads for wood working machines; and is designed to provide a cheap and efficient device of this character, in which the knives are securely held in their seats by 25 means of a keeper, which is in turn held in place by an auxiliary keeper.

A further object of my invention is to so arrange the keeper and auxiliary keeper that they can be removed from the seat in a 30 radial direction when the knife or cutter has been removed from the seat.

The precise nature of my invention will be best understood by reference to the accompanying drawings, which will now be described, it being premised, however, that changes may be made in the general arrangement of the parts, and details of construction, without departing from the spirit and scope of my invention as defined in the 35 appended claims.

Referring to Figs. 1 to 5, the numeral 2 designates a cutter head of cylindrical form, which is provided with a plurality of longitudinally disposed grooves 3. 4 are longitudinally disposed recesses opening into the grooves 3. Seated within each of these grooves 3 is a knife or cutter 5, which is retained in position by means of a keeper 6 and an auxiliary keeper 7. The keeper 6 is 45 provided with an arc shaped recess for the reception of the concave or arc shaped face of the auxiliary keeper 7. Extending tangentially through the wall of the cutter head 2 and opening into the grooves 3 are a 50 series of tapped openings 8, which are ar-

ranged to receive set screws 9, each of which is provided with a wrench socket 10. Interposed between each keeper 6 and its knife 5 is a spacer 11, although this spacer may be omitted and the knife made of the thickness 60 equal to the thickness of the keeper, plus that of the spacer. Extending tangentially through the walls of the cutter head 2 are a series of openings 12, which open into their respective knife seats and are arranged to 65 receive a wrench for adjusting the height of the knife, as hereinafter described.

The parts are assembled by first inserting the auxiliary keeper, after which the main keeper is inserted in place. The spacer 11, 70 together with the knife 5, are then placed in their proper positions, and the set screws for this knife are then moved inwardly to clamp the parts so as to retain them within the seat, but not sufficiently to positively 75 lock them. A wrench 13, such as is shown in Fig. 5, is then inserted into one of the openings 12 at the end of the cutter head, and the knife 5 is adjusted by means of the projection 14 which engages the bottom edge 80 of the knife, and by turning this wrench, the knife can be raised to its proper position. The wrench is then inserted in the various openings through the cutter head for adjusting the other portions of this knife, and 85 after the knife has been leveled the wrench is removed and the set screws forced home by inserting the projection 15 of the wrench into the sockets 10 of the set screws, and jamming them against the auxiliary keeper. 90

The auxiliary keeper 7 is provided with a projecting face 16 which is arranged to engage the wall of the knife seat, and the set screws engage a flat face of this auxiliary keeper, and when said screws are forced inwardly, the auxiliary keeper will be forced against the circular shaped recess in the keeper 6 and force the keeper against the cutter 5. As soon as the forward movement of the keeper 6 has been arrested, the auxiliary 100 keeper will be slightly rotated in the groove, the projecting face 16 engaging the wall of the seat, this portion forming a fulcrum so that a lever action is obtained between this point and the point engaged by the screws, 105 to force the keeper against the knife or cutter.

In Fig. 6, I have shown a modified form in which all of the various parts have been given the same reference characters with the 110

letter *a* affixed. In this figure, the keeper 6^a is provided with a projection 6^b which is seated in a recess 6^c in the cutter head. The auxiliary keeper 7^a is triangular in cross section and is seated in the undercut recess 4^a.

In both of these constructions, the main keepers and auxiliary keepers are locked from radial movement. When it is desired to remove the parts, the cutters are first removed, then the keeper is removed, after which the auxiliary keeper can be removed; the arrangement being such that all of these parts can be removed in a radial direction, in the above order.

15. The advantages of my invention result from the provision of the keeper which can be removed from the knife seats in a radial direction after the knife or cutter has been removed therefrom, and which is locked from radial movement when the cutter is in its seat. Further, from the provision of means for applying pressure to the keeper throughout its full length to clamp the knife in its seat.

25. I claim:

1. A cutter head having a longitudinally disposed knife groove extending the full length of the cutter head, there being an undercut longitudinally disposed recess 36 opening into said groove and extending the full length of the cutter head, a knife in said groove, a main keeper for said knife within the groove, said keeper being approximately the length of the knife, an auxiliary keeper 35 within said recess and approximately the same length as the main keeper, in engagement with one side of the keeper and having a wedging engagement with a portion of the wall of the recess and said keeper, and means for forcing the auxiliary keeper inwardly against the main keeper and the wall of the recess to clamp the knife within its seat, substantially as described.

2. A cutter head having a longitudinally

disposed knife groove extending the full length of the cutter head, there being an undercut longitudinally disposed recess opening into said groove and extending the full length of the cutter head, a knife in said groove, a main keeper for said knife within the groove, an auxiliary keeper within said recess in engagement with a portion of the keeper and a portion of the wall of the recess, there being a plurality of tangentially disposed screw threaded openings in the cutter head opening into said recess, and screws within said openings arranged to be moved downwardly to force the auxiliary keeper against a portion of the wall of the recess and the auxiliary keeper to clamp the knife within its seat, substantially as described.

3. A cutter head having a longitudinally disposed knife groove extending the full length of the cutter head, an undercut recess opening into said groove and extending the full length of the cutter head, a knife in said groove, an auxiliary keeper of triangular cross section seated within the undercut portion of the recess and extending approximately the full length of the main keeper, 76 said auxiliary keeper having one face in engagement with the main keeper and another face in engagement with one wall of the recess, there being a plurality of screw threaded tangential openings extending outwardly 75 from said recess through the wall adjacent to the other side of the auxiliary keeper, and screws within the said openings arranged to engage the last mentioned side of the auxiliary keeper to force it downwardly against the main keeper and wall of the recess, substantially as described.

In testimony whereof, I have hereunto set my hand.

CLINTON G. WILDERSON.
